(57) **CLAIM**

The ornamental design for a switch plate, as shown and described.

DESCRIPTION

FIG. 1 is a top front and left side perspective view of [an inner frame for a single switch plate] *a switch plate frame showing my new design*;
FIG. 2 is a front view thereof;
FIG. 3 is a top plan view thereof;
FIG. 4 is a right side view thereof [which is a mirror image of the left side] *the left side view being a mirror image thereof*;
FIG. 5 is a rear view thereof;
FIG. 6 is a bottom plan view thereof;
FIG. 7 is a top front and left side perspective view of [an inner frame for a double switch plate] *a second embodiment of a switch plate frame showing my new design*;
FIG. 8 is a front view thereof;
FIG. 9 is a top plan view thereof;
FIG. 10 is a right side view thereof [which is a mirror image of the left side] *the left side view being a mirror image thereof*;
FIG. 11 is a rear view thereof;
FIG. 12 is a bottom plan view thereof;
FIG. 13 is a top front and left side perspective view of [an inner frame for a triple switch plate] *a third embodiment of a switch plate frame showing my new design*;
FIG. 14 is a front view thereof;
FIG. 15 is a top plan view thereof;
FIG. 16 is a right side view thereof [which is a mirror image of the left side] *the left side view being a mirror image thereof*;
FIG. 17 is a rear view thereof;
FIG. 18 is a bottom plan view thereof;
FIG. 19 is a top front and left side perspective view of [an inner frame for a quadruple switch plate] *a fourth embodiment of a switch plate frame showing my new design*;
FIG. 20 is a front view thereof;
FIG. 21 is a top plan view thereof;
FIG. 22 is a right side view thereof [which is a mirror image of the left side] *the left side view being a mirror image thereof*;
FIG. 23 is a rear view thereof; and,
FIG. 24 is a bottom plan view thereof.
